UNITED STATES PATENT OFFICE.

HANS RICHTER, OF BEHRINGERSDORF, NEAR NUERMBERG, GERMANY, ASSIGNEE, BY
MESNE ASSIGNMENTS, TO WESTINGHOUSE ELECTRIC & MANUFACTURING COMPANY, A CORPORATION OF PENNSYLVANIA.

CLOSED ELECTRIC MACHINE.

Application filed November 7, 1925, Serial No. 67,653, and in Germany November 7, 1924.

My invention relates to a closed electric machine which works immersed in a liquid and more particularly to a mine pump motor.

5 For raising naphtha, brine, water or the like from bore holes, electrically driven mine pumps are employed which are inserted into the bore holes, together with the delivery pipe, and immersed in the liquid. The driving motor, which as a rule is located below the pump, is cooled by the liquid sucked up. The liquid should, however, not penetrate between the active parts of the motor. For this purpose, the motor is encased, and the 10 shaft of the motor is passed into the pump chamber through a stuffing box. It has, however, been found that the packing of the stuffing box exerts a strong braking action upon the shaft and thus upon the motor, and 15 that the packing becomes excessively heated if it is sufficiently tight to fulfill its purpose.

In order to eliminate this waste of energy, a perfectly acting shaft packing is abandoned, according to my invention, and the penetration of a small quantity of the liquid into the machine is permitted. To neutralize this as far as possible, provisions are, however, made which render the penetration 20 of the liquid into the bearings and windings impossible, or at least difficult, as well as the collection of the liquid in the immediate vicinity of the active parts of the motor. The liquid which has penetrated through 25 the packing is collected in a receptacle which is drained by a bilge pump coupled with the motor, in a known manner.

To prevent a drowning of the machine during intervals in the operation of the mine 30 pump and while the bilge pump is stopped, the passage of the shaft is sealed in a known manner by a valve which closes automatically when the machine is stopped, but which is raised off its seat when the machine 35 is started again, in order to avoid friction losses.

The object of my invention is to provide a closed electrical machine, adapted to operate while immersed in a liquid, with a particularly simple, but suitably designed, device for protecting the active parts against the penetrating liquid.

During intervals in the service, the passage of the shaft is closed by a valve. Ac-

cording to my invention, the valve disc surrounding the shaft is tightly and firmly mounted upon the shaft and both the valve disc and the shaft are displaceable in an axial direction. The shaft thus forms the valve rod and ensures a good guidance of the valve disc. The valve seat consists of a member tightly fitting the casing and surrounding the shaft annularly. This valve is distinguished from known designs by extreme simplicity and reliability in operation. 55 When the pump is started, the valve disc is raised off its seat by a centrifugal governor in a known manner. This governor, according to my invention, is located in the interior of the casing and is in operative engagement with the shaft of the machine. As soon as a predetermined speed is attained, the governor displaces the shaft in relation to its 60 bearings and thus lifts the valve disc off its seat. 65

Another object of my invention is the cleaning of the seat of the valve. According to my invention, the valve is placed in the path of the penetrating liquid between the stuffing box of the shaft passage and the 70 collecting receptacle for the liquid which has already penetrated the stuffing box. This arrangement has the advantage that the stuffing box acts as a filter and prevents 75 impurities suspended in the liquid from 80 entering the valve.

On account of the small diameter of the bore holes, the machine is of elongated narrow design. The shaft is vertical while the machine is in service. If the shaft extends 85 out at the top of the motor, the collecting receptacle for the penetrated liquid is preferably located below the machine and is connected with the shaft passage by a channel or duct traversing the sheet-iron stampings 90 of the stator member.

The vertical shaft permits the utilization of the weight of the rotor for closing the valve. According to my invention, the valve disc is pressed down upon its seat by the 100 weight of the rotor. The centrifugal governor then raises the rotor at a predetermined speed. For lifting the rotor, the magnetic pull which the stator exerts upon the rotor may equally well be utilized.

An embodiment of my invention is illustrated in the drawing affixed hereto, wherein Fig. 1 is a vertical sectional view of the

upper part of a sinking pump or mine pump motor according to my invention, and

Fig. 2 is a similar view of the lower part thereof.

Referring to the drawing, it will be seen that the sheet-iron stampings 2 of the stator member are pressed into a continuation 1 of the pipe line. The stator winding 3 is supplied with current at 4. The squirrel-cage rotor member 5 with the shaft 6 is journaled at 7 and 8 in journal bearings upon rollers which permit an axial displacement of the shaft to a small extent. During operation, the shaft 6 is supported by the noses 10, 11 of the centrifugal weights 12, 13 through the agency of the sleeve or bushing 9. The centrifugal weights are rotatably mounted at 14 and 15 upon the ring 16 which is supported upon the thrust ball-bearing 17. In the inoperative position, the fly-weights rest upon the sleeve 9. The journal bearing 7 is protected against the entry of liquid or the escape of the bearing lubricant by the packings 18, 19; the journal bearing 8 by the packings 20, 21; and the thrust-bearing 17 furthermore also by the packing 22. The bearing 7 and the packings 18 and 19 are supported by the parts 23, 24, the bearings 8, 17 and the packings 20, 21, 22 by the parts 25 and 26. The parts 23 to 26 are mounted upon the pipe sections 27 and 28 which are joined to the pipe 1 by the sleeves 29 and 30. The whole arrangement is closed at the top by the end member 31 and at the bottom by the receptacle or container 32. The top member 31 is provided with a stuffing-box 33 through which the motor shaft 6 extends. The shaft is carried upward to the pump of which only the coupling 34 is indicated in the drawing. Below the stuffing-box 33 a valve disc 35 is mounted on the shaft 6 by means of a key and an annular nut 37. The liquid penetrating through the stuffing-box 33 collects, during intervals in the service, in the annular chamber 38, and flows, during the operation of the pump, through the opened valve 35 and the channel 39, 40, into the enlarged top end of a tube 41 which extends through the stator winding 3 and the stator stampings 2. From the tube 41, the liquid flows through the chamber 42, 43 and the opening 44 into the container 32. From the lowest place 45 of the container 32, the fluid is discharged, through a vertical tube 46, by means of an auxiliary pump 47 which forces the fluid through a valve 48. The tube 46 and the auxiliary pump 47 are attached to the motor shaft 6. The valve disc 35 rests on a seat 36 on the part 24 during the intervals in the service.

The device operates in the following manner: during the normal service, the shaft 6, carrying the valve disc 35, is raised by the centrifugal weights 12 and 13, in order to prevent rubbing contact of the disc with its

seat. The liquid which has penetrated through the stuffing-box 33 passes into the container 32 in the manner described, and is continually drained out of it by means of the auxiliary pump 47. After the motor has been switched off, the centrifugal weights 12, 13 approach each other under the action of the weight of the rotor and the shaft and allow the shaft to drop until the valve disc 35 rests upon its seat at 36. The weight of the rotor and the shaft exert a pressure upon the valve disc. During the service intervals, the liquid penetrating through the top stuffing-box 33 is caught in the annular chamber 38 above the valve disc 35. The valve 35, 36 prevents the liquid from penetrating into the interior of the motor, through the packings 18 and 19. When the motor is started again, the centrifugal weights 12, 13 raise the shaft 6 with the valve 35, and the liquid which has collected in the chamber 38 flows through the valve into the container 32 in the manner specified above. From there it is discharged from the motor by the auxiliary pump 47. The normal service state is thereby resumed again.

The valve 35, 36 may be located above the stuffing-box 33, but the design illustrated is preferable because the stuffing-box 33 prevents the entry of sludge and sand into the seat of the valve, in the manner of a filter.

Various modifications may be made in the device, embodying my invention without departing from the spirit and scope thereof and I desire that all such modifications shall be included in the appended claims which are to be limited only by the prior art.

I claim as my invention:

1. In a closed electrical machine adapted to operate immersed in a liquid and comprising a collecting vessel for the liquid penetrating through the stuffing box of the shaft and a valve adapted to seal said stuffing box when the shaft is inoperative and to be raised off its seat when said shaft is operative, a valve disc tightly mounted upon said shaft and adapted to be moved axially together with said shaft and a centrifugal governor located within the machine casing and adapted to displace said shaft in relation to its bearings and to control said valve.

2. In a closed electrical machine adapted to operate immersed in a liquid and comprising a collecting vessel for the liquid penetrating through the stuffing box of the shaft and a valve adapted to seal said stuffing box when the shaft is inoperative and to be raised off its seat when said shaft is operative, a valve disc tightly mounted upon said shaft and adapted to be moved axially together with said shaft and a centrifugal governor located within the machine casing and adapted to displace said shaft in relation to its bearings and to control said valve.

3. In a closed electrical machine adapted to operate immersed in a liquid and comprising a collecting vessel for the liquid penetrating through the stuffing box of the shaft and a valve adapted to seal said stuffing box when the shaft is inoperative and to be raised off its seat when said shaft is operative, a valve disc tightly mounted upon said shaft and adapted to be moved axially together with said shaft and a centrifugal governor located within the machine casing and adapted to displace said shaft in relation to its bearings and to control said valve, said valve being located be-

tween said stuffing box of the shaft and said collecting vessel for the liquid which has penetrated into said machine casing.

3. In a closed electrical machine adapted to operate immersed in a liquid with a vertical shaft carried through at the top and comprising a collecting vessel for the liquid penetrating through the stuffing box of the shaft and adapted to be drained by a bilge pump and a valve adapted to seal said stuffing box when the shaft is inoperative and to be raised off its seat when said shaft is operative, a valve disc tightly mounted upon said shaft and adapted to be moved axially together with said shaft and a centrifugal weight located within the machine casing and adapted to displace said shaft in relation to its bearings and to control said valve, said valve being located between said stuffing box of the shaft and said collecting vessel for the liquid which has penetrated into said machine casing, said collecting vessel being located below said machine, and sheet-iron stampings, in the machine containing a channel adapted to put said collecting vessel in communication with said stuffing box.

4. In a closed electrical machine adapted to operate immersed in a liquid and comprising a collecting vessel for the liquid penetrating through the stuffing box of the shaft and a valve adapted to seal said stuffing box when the shaft is inoperative and to be raised off its seat when said shaft is operative, a valve disc tightly mounted upon said shaft and adapted to be pressed upon its seat by the weight of the rotor of said machine, and a centrifugal governor located within the machine casing and adapted to raise said rotor at a predetermined speed of said shaft, said valve being located between said stuffing box of the shaft and said collecting vessel for the liquid which has penetrated into said machine casing, said collecting vessel being located below said machine, and sheet-iron stampings in the machine containing a channel adapted to put said collecting vessel in communication with said stuffing box.

5. A submersible motor having an enclosing casing, a shaft extending out of said casing, an imperfect packing for the shaft, a reservoir at the bottom of the casing for collecting fluid which enters the casing and for keeping said fluid out of contact with the vital parts of the motor, and means for expelling the fluid from said reservoir.

6. A submersible motor having an enclosing casing, a shaft extending out of said casing, an imperfect packing for the shaft, a reservoir at the bottom of the casing for collecting fluid which enters the casing and for keeping said fluid out of contact with the vital parts of the motor, a substantially fluid-tight, releasable valve member sur-

rounding said shaft and operable to eliminate substantially all leakage, means for, at times, releasing said valve member whereby the frictional drag on said motor may be materially reduced, and means for expelling the fluid from said reservoir.

7. A submersible motor having an enclosing casing, a shaft extending out of said casing, an imperfect packing for the shaft, a reservoir at the bottom of the casing for collecting fluid which enters the casing and for keeping said fluid out of contact with the vital parts of the motor, a substantially fluid-tight, releasable valve member surrounding said shaft and operable to eliminate substantially all leakage, means for, at times, releasing said valve member whereby the frictional drag on said motor may be materially reduced, and means coupled to said shaft for expelling the fluid from said reservoir.

8. A submersible motor having an enclosing casing, a shaft extending out of said casing, an imperfect packing for the shaft, a reservoir at the bottom of the casing for collecting fluid which enters the casing and for keeping said fluid out of contact with the vital parts of the motor, a substantially fluid-tight, releasable valve member surrounding said shaft and operable to eliminate substantially all leakage, automatic means for causing said valve member to be closed when the motor is at rest and for causing said valve member to be released when the motor is operated, whereby the frictional drag on the motor may be materially reduced, and means for expelling the fluid from said reservoir.

9. A submersible motor having an enclosing casing, a shaft extending out of said casing, an imperfect packing for the shaft, a reservoir at the bottom of the casing for collecting fluid which enters the casing and for keeping said fluid out of contact with the vital parts of the motor, a substantially fluid-tight, releasable valve member surrounding said shaft and operable to eliminate substantially all leakage, automatic means for causing said valve member to be closed when the motor is at rest and for causing said valve member to be released when the motor is operated, whereby the frictional drag on the motor may be materially reduced, and means coupled to said shaft for expelling the fluid from said reservoir.

10. A submersible motor having an enclosing casing, a shaft extending out of said casing, variable leakage-preventing means surrounding said shaft, means responsive to the operation of the motor for varying said leakage-preventing means from a substantially fluid-tight, heavy friction joint to a relatively leaky, light-friction joint, a reservoir at the bottom of the casing for col-

lecting fluid which enters the casing and for keeping said fluid out of contact with the vital parts of the motor, and means for expelling the fluid from said reservoir.

11. A submersible motor having an enclosing casing, a shaft extending out of said casing, variable leakage-preventing means surrounding said shaft, means responsive to the operation of the motor for varying said leakage-preventing means from a substan-

tially fluid-tight, heavy-friction joint to a relatively leaky, light-friction joint, a reservoir at the bottom of the casing for collecting fluid which enters the casing and for keeping said fluid out of contact with the vital parts of the motor, and means coupled to said shaft for expelling the fluid from said reservoir.

In testimony whereof I affix my signature.

HANS RICHTER.
